(57) **CLAIM**

I claim the ornamental design for a nail gun stabilizer, as shown and described.

DESCRIPTION

FIG. 1 is a top plan view of a nail gun stabilizer embodying my new design;

FIG. 2 is a front elevation view thereof;

FIG. 3 is a rear elevation view thereof;

FIG. 4 is a bottom plan view thereof;

FIG. 5 is a left side elevation view thereof;

FIG. 6 is a right side elevation view thereof;

FIG. 7 is a top, front and left side perspective view thereof; and,

FIG. 8 is a left side elevation view thereof as it appears with an exemplary nail gun.

The broken lines appearing on FIG. 8 of a nail gun are environmental matter forming no part of the claimed design.
